WATER COOLER

Charlotte S. Knight, Merrick, N. Y.

Application November 23, 1934, Serial No. 754,515

17 Claims. (Cl. 62—142)

The present invention relates to water coolers and more particularly to those for cooling water before it passes to a drinking fountain.

An object of the invention is to provide a water cooler particularly adapted for use in office buildings, although it may be used in any capacity where cooled drinking water is desirable.

Another object is the provision of a cooler so designed that solidified carbon dioxide or dry ice may be economically utilized as the refrigerant.

A further object is to provide a water cooler that is simple in construction, and which may be easily and quickly charged with refrigerant and operated with minimum attention.

With the foregoing and other objects in view, the invention will now be more fully described, reference being had to the accompanying drawings, in which:

Figure 1 is a side elevation of the preferred embodiment of my invention;

Figure 2 is a vertical section thereof;

Figure 3 is a detail of the means for securing the feeding device to its shaft;

Figure 4 is a side elevation partly in section of a modified form of my invention;

Figure 5 is a detail view of the closure plate used in the form shown in Figure 4;

Figure 6 is another modification showing the use of a filter in connection with the water reservoir;

Figure 7 is an end view thereof; and

Figure 8 is another modification showing the use of a filter positioned below the water reservoir.

Referring to Figures 1 and 2, there is illustrated the preferred embodiment of my invention in which the numeral 10 designates a water cooler comprising a water reservoir 11 having an inlet 12 in its base and an outlet 13 in its top wall leading to a drinking fountain 14. The upper wall 15 of the reservoir is provided with an opening 16 through which is inserted the lower portion or section 17 of a refrigerant receptacle 18.

The refrigerant receptacle is also provided with a section projecting above the wall 15 of the reservoir and constituting a storage compartment 19. This compartment is separated from the inner or lower compartment 17 by means of a feeding device 20 which also constitutes a partition between the two compartments. While different types of feeding devices may be utilized, I prefer the one disclosed in the drawings. This comprises a sphere or ball 21 having a roughened surface and mounted for rotary movement within the refrigerant receptacle above the wall 15 of the reservoir. The means for rotating the feeding device 20 comprises a rod or shaft 22, passing through the center of the ball and secured thereto by a machine screw 23. The ends of the shaft 22 are journalled in opposite walls of the refrigerant

receptacle and one end thereof is extended and projects through a suitable packing box 24. This shaft end comprises a crank or handle 25 which upon rotary movement actuates the feeding device for a purpose to be hereinafter described.

In each embodiment of my invention I form the refrigerant receptacle into two separate sections or compartments. The lower compartment 17 extends substantially to the bottom wall of the reservoir 11 and is fixedly secured thereto with its upper edge turned outwardly to form a flange 26. This flange rests upon the outside of the top wall 15 of the reservoir and may be secured thereto in any suitable manner. For purposes of convenience, the upper and lower compartments are of cylindrical formation, with the upper compartment being of a diameter slightly less than that of the lower one to permit the lower portion 27 of the upper compartment to be inserted within the lower compartment 17. The upper compartment is provided with an annular flange 28 positioned above its lower extremity and this flange contacts with the flange 26 and rests thereupon when the refrigerant receptacle is assembled. This constitutes a very satisfactory form of slip joint which effectively seals the refrigerant receptacle from the atmosphere. It is to be understood that the lower compartment 17 is entirely sealed and out of communication with the interior of the reservoir 11.

The purpose of detachably connecting the upper or refrigerant storage compartment to the lower section 17 is to permit a preliminary charge of the refrigerant, which preferably is a disc or wafer of solidified carbon dioxide or dry ice, to be inserted in the lower section 17. This is to preliminarily cool the water contained in the reservoir 11. The storage compartment 19 is packed with dry ice and after the preliminary charge has sufficiently cooled the water in the reservoir, it is merely necessary for anyone who desires to use the drinking fountain 14 to rotate the handle 25 several revolutions. This will rotate the feeding device 20, which, by reason of the roughened surface, will chip off particles of the dry ice in the storage compartment and permit them to drop by gravity to the lower section 17. It will thus be apparent that the water issuing to the drinking fountain 14 may be cooled with a minimum of attention, the only requisite being that a charge of dry ice be inserted in the storage compartment and a preliminary wafer placed in the lower compartment 17. While my cooler is designed for universal use, it is particularly adapted for office buildings. In this connection, the preliminary charge or wafer may be inserted in the lower compartment in the morning and thereafter the water in the reservoir will be maintained sufficiently chilled by the

transfer of small particles of dry ice from the storage compartment to the lower section 17.

Preferably, the reservoir 11 is double walled to permit an insulating packing 29 to be secured between the walls. Furthermore, the storage compartment 19 or that portion of the refrigerant receptacle projecting above the reservoir, is also of double wall construction with suitable insulating material 30 packed between the walls. An insulated cover 31 is provided to close the upper end of the refrigerant receptacle.

In order that the dry ice in the storage compartment will at all times contact with the ball 21, a suitable spring 32 is positioned in the top 15 of the storage compartment between the cover 31 and the store of dry ice. The upper end of the spring is preferably secured to the cover while the lower end is connected to a plate 32' which, when in position, presses against the dry ice.

Referring to Figure 4, I have illustrated a modification in which the refrigerant receptacle is formed as an integral unit instead of comprising detachable sections as described in connection with Figures 1 and 2. In this form, the water 20 reservoir 33 supports the refrigerant receptacle 34 with the lower section or compartment 35 projecting within the interior of the water reservoir. The feeding device 36 constitutes a partition for separating the lower compartment from 25 the upper or storage compartment 37 as in the other embodiment. In this form of the device the refrigerant receptacle is provided with an opening 38 positioned between the upper wall of the reservoir and the feeding device 36. The 30 opening is closed by a slide plate 39 having an opening 40 of the same diameter as the inner wall of the receptacle. To permit the easy insertion and removal of the slide plate 39, it is provided with an integral handle 41 having a 35 combined stop and sealing flange 42 which securely closes the opening 38 against the atmosphere.

In use, when it is desired to insert a preliminary charge into the lower compartment 35, it is merely 40 necessary to remove the side plate 39 and slip the dry ice wafer or disc through the opening 38 and then return the slide to the position shown in Figure 4. Thereafter the feeding device is actuated whenever it is desired to use the drinking 45 fountain.

In Figure 6, there is illustrated a combined cooler and filter. In this arrangement, the water reservoir is formed in two sections, one section 43 supporting the refrigerant receptacle 44 and the 50 other section 45 supporting the drinking fountain 46. The walls of both sections are insulated as in the other forms and the inner wall 47 of the section 45 constitutes a filter casing for receiving a substantially dome-shaped filtering element 48 55 similar to that shown in my copending application Serial No. 725,358, filed May 12, 1934.

The section 43 is provided with a supporting and clamping plate 49 at its open end and when the sections are placed in the position shown in 60 Figure 6, the filtering element is securely clamped between the plate 49 and the casing 47 by means of suitable wing nuts and bolts 50.

With this arrangement, it is apparent that the water entering the reservoir through the inlet 51 65 is not only cooled by the dry ice in the refrigerant receptacle, but is also filtered before it passes through the outlet 52 to the fountain 46. Furthermore, by reason of having the filter constitute a portion of the water reservoir, there is no 70 chance for the water to become warm before it

issues to the fountain. It is further apparent that both the refrigerant receptacle and the filter may be easily and quickly detached with a minimum amount of time and trouble.

In Figure 8, I have illustrated a combined water cooler and filter in which the filter casing 53 is positioned below the water reservoir 54. The refrigerant receptacle 55 is similar to that illustrated in Figures 1 and 2.

While I have designated my invention as a water cooler and referred to it as such in the specification and claims, it is to be understood that it may be utilized for cooling various liquids and that the term water is used broadly.

I claim:—

1. In a water cooler, a water reservoir having inlet and outlet passages, a refrigerant receptacle having a section thereof projecting within said reservoir and out of communication therewith, said receptacle having a section comprising a refrigerant storage compartment disposed exteriorly of the reservoir, and a movable partition between the two sections for controlling the discharge of refrigerant from one to the other.

2. In a water cooler, a water reservoir having inlet and outlet passages, a refrigerant receptacle supported intermediate its ends by a wall of the reservoir and having a section thereof projecting within said reservoir and out of communication therewith, said receptacle having a section comprising a refrigerant storage compartment disposed exteriorly of the reservoir, and a movable partition between the two sections for controlling the discharge of refrigerant from one to the other.

3. In a water cooler, a water reservoir having inlet and outlet passages, a refrigerant receptacle supported intermediate its ends by the top wall of the reservoir and having its lower portion projecting vertically within the reservoir and terminating adjacent the bottom wall thereof, the upper portion of said receptacle comprising a refrigerant storage compartment disposed exteriorly of the reservoir, and a movable partition between the upper and lower portions of the receptacle for controlling the discharge of refrigerant from one to the other.

4. In a water cooler, a water reservoir having inlet and outlet passages, a refrigerant receptacle having a section thereof projecting within said reservoir and out of communication therewith, said receptacle having a section comprising a refrigerant storage compartment disposed exteriorly of the reservoir, and means carried by said receptacle and controlling the discharge of the refrigerant from the storage compartment to the section thereof positioned within the reservoir.

5. In a water cooler, a water reservoir having inlet and outlet passages, a refrigerant receptacle having a section thereof projecting within said reservoir and out of communication therewith, said receptacle having a section comprising a refrigerant storage compartment disposed exteriorly of the reservoir, and a feeding device positioned within said receptacle and separating the storage compartment from the lower section of the receptacle, said feeding device controlling the discharge of the refrigerant from one compartment to the other.

6. In a water cooler, a water reservoir having inlet and outlet passages, and a refrigerant receptacle supported intermediate its ends by the top wall of the reservoir and having its lower portion projecting vertically within the reservoir and terminating adjacent the bottom wall thereof, the upper portion of said receptacle comprising

CHARLOTTE S. KNIGHT.
